(57) **CLAIM**

The ornamental design for a surveillance camera for an automobile, as shown and described.

DESCRIPTION

FIG. 1 is a front perspective view of a surveillance camera for an automobile showing my new design;

FIG. 2 is a front view thereof;

FIG. 3 is a rear view thereof;

FIG. 4 is a top plan view thereof;

FIG. 5 is a bottom plan view thereof;

FIG. 6 is a right side elevational view thereof, the left side elevational view being a mirror image thereof;

FIG. 7 is a perspective view of a surveillance camera for an automobile according to a second embodiment of the present design;

FIG. 8 is a front view thereof;

FIG. 9 is a rear view thereof;

FIG. 10 is a top plan view thereof;

FIG. 11 is a bottom plan view thereof; and,

FIG. 12 is a right side elevational view thereof, the left side elevational view being a mirror image thereof.
